UNITED STATES PATENT OFFICE

ALEXANDER HARRIS, OF NEWARK, NEW JERSEY, ASSIGNOR TO ART METAL WORKS, INC., A CORPORATION OF NEW JERSEY

SIGN

Application filed August 9, 1928. Serial No. 298,479.

This invention relates to signs and more particularly to one in which the light is received on a stencil plate and transmitted from the device by reflection from a mirror surface.

The main object of the invention is to provide a simple and efficient device for use as a sign or as a signalling device whereby signals can be readily transmitted or multi-colored symbols can be exhibited or advertised at will and the operation of the device controlled either directly by hand or from a distance by any suitable means. Incidentally the device is also particularly adapted to be used as a signalling device for automobiles.

Further and more specific objects, features and advantages will more clearly appear from the detailed description given below taken in connection with the accompanying drawings which form part of this specification, and which illustrate one embodiment of the invention, and in which Fig. 1 is a perspective view of a device embodying the improvements in one form and with one of the control shutters open;

Fig. 2 is a rear elevation of the device showing one of the control shutters open;

Fig. 3 is a transverse vertical section;

Fig. 4 is an enlarged section taken on the line 3—3 of Fig. 2 showing the details of the construction and arrangement of the control shafts and lever arms; and,

Fig. 5 is a transverse vertical section through a modified form of the invention.

The device, as shown in Figs. 1 to 4, comprises a casing of sheet metal having top and bottom walls 10 and 11 and side walls 12 and 13. The walls 10 and 11 are disposed at an angle to each and at their rear edges are connected together. The front face of this chamber is open. The top wall 10 is cut out and disposed therein is a stencil plate or, as shown, a pair of such plates 14 and 15 which may be of colored material such as glass or other light transmitting substance not necessarily transparent. These stencils are held in place by clips 16. Normally covering the stencils 14 and 15 are control shutters 17 and 18 which are pivotally mounted for operation by arms 19 and 20 to which are connected

links or cords 21 and 22 for manual manipulation from a distance. It is obvious that these shutters may be operated either under manual or automatic control or by any other means such as electrical devices, not shown. 55 The stencils may be of differently colored glass such as red and green glass, and they may be provided with symbols such as "Stop" and "Go" signs, the "Go" sign being under the shutter 17 as at 23, and a "Stop" sign 60 under the shutter 18. It is apparent that either or both of the cords 21 and 22 may be operated as desired so that the stencils will be separately exposed to the sunlight or to any other source of light thrown thereon, the 65 light being transmitted through the stencils respectively and the signs accordingly reflected from the mirror 37 as desired.

Arm 19 is fastened to sleeve 24 journalled in bearing 25 fastened to the top wall 10. To sleeve 24 are connected collars 26 and 27 on shutter 17, and fastened thereto by set screws 28 and 29. Arm 20 is fastened to stem 30 loosely mounted within sleeve 24 and at its outer end journalled in bearing member 31 fastened to the top wall 10. A collar 32 on the shutter 18 is fastened to the stem 30 by means of set screws 33 and 34, passing through slots 35 and 36 in the sleeve 24. Thus the shutters are arranged and constructed to 70 be operated at will by pulling on the cords or 75 links 21 and 22.

On the bottom wall 11 is disposed a reflecting surface of mirror glass or of polished metal 37, held in place by means of clips 38. 85 The casing may be supported from any desired base such as a signal post controlled by a traffic officer to signal "Stop" and "Go". Or it may be supported on the rear of an automobile body by means of an adjustable bracket 39, by means of which the device may be 90 adjusted for universal movement on a supporting member on the automobile.

In order to illustrate the operation of the device in this connection, I will assume that 95 it is to be used on the back of an automobile as a signal means such as a stop and warning light, and one which is very useful during the day time when ordinary stop and warning lights are rather ineffective. As the driver 100

proceeds and wishes to signal a warning to the driver in the rear he may operate one of the shutters by exerting a pull on one of the cords or links by any suitable means not shown, and thus expose to the sunlight the plate or stencil thereunder. This plate may be of green colored glass and have on it the letter W to give warning of an impending change in the direction, or speed of the vehicle. The sunlight pouring down on the stencil will pass through it and hit the mirror 37 and thereby reflect the sign rearwardly toward the rear driver. If a stop signal is to be transmitted, then the other shutter may be manipulated and a red stencil with the letter S or any other symbol thereon may be exhibited to the sunlight and, as before, reflected rearwardly from the mirror 37. It is also apparent that the device can with advantage be used in the daytime to transmit other traffic or changing signals of any kind and can also be used at night when employed with suitable sources of light. If desired, the shutters may be returned to closed position by suitable springs, not shown.

The form of the invention shown in Fig. 5 is a modification in which the shutters are constructed as before but are arranged to pivot about an axis lengthwise of the casing instead of cross-wise as in the form shown in Figs. 1 to 4. In this form the stencils are arranged one in front of or above the other instead of at the side of each other as above described. If desired the shutters 17 and 18 may be rigidly secured together so that when one is opened the other is closed and vice versa.

While I have described my invention in detail and with respect to preferred forms thereof, I do not desire to be limited to such details or forms since many changes and modifications may be made and the invention embodied in other forms without departing from the spirit and scope of the invention in its broader aspects. Hence I desire to cover all modifications and forms coming within the language or scope of any one or more of the appended claims.

What I claim as new and desire to secure by Letters Patent is:

50. 1. In combination with a casing having a top and bottom wall angularly disposed and with a front opening, light transmitting plates in the top wall, each of said plates adapted to convey different information to an observer, a mirror disposed on the bottom wall to receive the transmitted light and reflect it through the front opening, shutters mounted on the casing to prevent transmission of light through said plates, and means 60. for independently operating said shutters to open and close them at will.

65. 2. In combination with a sign casing having a top and bottom wall angularly disposed and with a front opening, light transmitting plates in the top wall, each of said plates

adapted to convey different information to an observer, a mirror disposed on the bottom wall to receive the transmitted light and reflect it through the front opening, shutters pivotally mounted in shafts on said casing to prevent transmission of light through said plates respectively, arms on said shafts, and connections to said arms permitting the opening and closing of said shutters at will.

70. In testimony whereof I have signed my name to this specification.

ALEXANDER HARRIS.
